UNITED STATES PATENT OFFICE.

THEODORE P. DRESSER, OF MEDFORD, MASSACHUSETTS.

DESIGN FOR KNITTED GOODS.

SPECIFICATION forming part of Design No. 13,327, dated October 3, 1862.

Application filed May 18, 1862. Term of patent 7 years.

To all whom it may concern:

Be it known that I, THEODORE P. DRESSER, of Medford, county of Middlesex, State of Massachusetts, have invented and produced a new 5 and original Design for Knitted Goods, of which the following, in connection with the photographs accompanying and forming a part hereof, is a full, clear, concise, and exact description.

10 In the photographs, Figure 1 shows the design repeated several times on the wrist part of a mitten. Fig. 2 shows the design on the edge of a piece of fabric.

15 My design is wrought into the knitted fabric by the machine under the manipulation of the operator. As is well known to all familiar with knitting or with knitted fabrics, each line of stitches is apparent to the eye, and, if what is known as the "Cardigan lock-stitch" 20 is used, may be made to stand out, and thus gives the fabric a ribbed surface. In such goods each line of stitches becomes very distinct and easily perceptible. I use these ribs or lines of stitches by giving them a peculiar 25 direction, as shown in the photographs, to produce my design.

The main feature of my design consists in the three parts or bands A, B, and C, which are knit continuously, and which may be of 30 one or various colors. I find it desirable for the best effects to use two harmonious colors, the central band, B, being, say, white, while

the bands A and C are red or blue. The ribs of the central band, B, I make to cross it at right angles, while the ribs of the bands A 35 and C, I make to cross those bands diagonally, the one running in the reverse diagonal direction from the other, as shown. At the edge of the goods, and next to the band A, I add a border, D, and into this border I knit two 40 threads of silk or yarn of a different color from either the border or the band A. This gives two dotted lines, E E, parallel to each other along the border, as shown in the drawings. The bands A and C, on either side of the central band, B, being ribbed diagonally, and the 45 line of the ribs of one being the reverse of that of the other, produces a shaded effect when viewed obliquely.

I claim—

1. In a design for knitted fabrics, the three parts or bands A, B, and C, each with a ribbed surface, the ribs crossing the side bands diagonally, and those on one band in a reverse diagonal direction from those on the other, and crossing the central band more nearly at right angles, all as shown and described. 50

2. The three bands A, B, and C, ribbed as shown, in combination with the dotted lines E E, as herein shown and described. 55

THEODORE P. DRESSER.
